Primary Examiner — Dana L Meyrow(74) *Attorney, Agent, or Firm* — Fulbright & Jaworski L.L.P.(57) **CLAIM**

The ornamental designs for cosmetic jar, as shown and described.

DESCRIPTION

FIG. 1 is a top perspective view of a first embodiment of my new design for a cosmetic jar;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a top perspective view of a second embodiment of my new design for a cosmetic jar, with the difference from the first embodiment (FIGS. 1–8) being the use of broken lines to illustrate the disc portion on the top surface of the cosmetic jar. The overall shape of the cosmetic jar of the second embodiment is identical to that of Embodiment 1 (FIGS. 1–8), excluding the top surface which has been disclaimed in Embodiment 2 (FIG. 9).
